UNITED STATES PATENT OFFICE.

ANDREW G. BRANDT, OF SCRANTON, PENNSYLVANIA.

POOL-TABLE.

1,387,345.

Specification of Letters Patent.

Patented Aug. 9, 1921.

Application filed July 21, 1920. Serial No. 397,816.

To all whom it may concern:

Be it known that I, ANDREW G. BRANDT, a citizen of the United States, residing at Scranton, in the county of Lackawanna and 5 State of Pennsylvania, have invented a new and useful Pool-Table, of which the following is a specification.

This invention relates to improvements in tables for use in playing pool or pocket billiards.

It is a well known fact among those acquainted with these games that balls when shot into the pockets often rebound onto the table instead of remaining in the pockets.

15 Although the ball will jump out of the pocket even though an excellent shot is made, the shot will not go to the credit of the player in spite of the fact that the loss of the shot is due to no fault on his part.

20 One of the objects of the present invention is to provide a simple and efficient means which can be applied readily to pool tables whereby the rebounding of the ball onto the table after entering the pocket is

25 prevented and, instead, the ball is directed positively in a downward direction, so as to become seated in the pocket or, where the table has runways leading to a ball box the ball will be positively directed into and

30 through the boot leading to the runway.

A further object is to provide a device of this character which will in no way detract from the appearance of the table or in any way conflict with the playing rules of the

35 games.

With the foregoing and other objects in view, which will appear as the description proceeds, the invention resides in the combination and arrangement of parts and in the 40 details of construction hereinafter described and claimed, it being understood that, within the scope of what is claimed, changes in the precise embodiment of the invention shown can be made without departing from the spirit of the invention.

In the accompanying drawings the preferred forms of the invention have been shown.

In said drawings—

50 Figure 1 is a plan view of a portion of a pool table having the present improvements applied to a side pocket.

Fig. 2 is a section on line 2—2, Fig. 1.

Fig. 3 is a section on line 3—3, Fig. 1.

55 Fig. 4 is a detail view of the deflecting plate forming a part of the attachment.

Fig. 5 is a section through a portion of a table having a boot in lieu of the pocket and which boot constitutes a deflecting attachment for the table.

60

Fig. 6 is a perspective view of a combined pocket bracket and guard plate forming a part of the attachment shown in Fig. 5.

Referring to the figures by characters of reference 1 designates a portion of the rail 65 of a pool table provided with the usual cushions 2 and pocket openings 3. In those types of tables utilizing pockets of netting or the like there are provided pocket brackets one of which has been indicated at 4,

70 each bracket including an intermediate arcuate portion 5 arranged across the opening 3, and oppositely extending arms 6 adapted to rest on the rail 1 within recesses 7 provided therefor. Bosses 8 are usually ex-

75 tended downwardly from these arms and into the rail as shown in Fig. 3, the said bosses being engaged by bolts 9 extending upwardly through the rail. A strip 10 of

leather or the like is wrapped about the intermediate arcuate portion 5 of the bracket and is laced or otherwise secured to the upper portion of the pocket 11 which, as before

stated, can be made of netting.

80 The construction heretofore described can be found in many pool tables but is objectionable because when a ball is directed into

85 the opening 3 it will often strike the leather covering 10 on the bracket 4 and rebound onto the table instead of dropping into the pocket. The present invention has for its

object, as before stated, to prevent this rebounding of the ball. One means employed for this purpose and which is intended to be used in connection with a pocket such as

90 95 has been described, includes an arcuate deflecting plate 12 provided, along the upper surface thereof and back from the upper end, with a transverse rib 13 above and spaced from a transverse bead 14. A strip 100

15 of leather or other suitable material is placed upon the concave surface of the plate 12 and is slightly dished as shown particularly in Fig. 2. The lower end of this strip

105 is folded over the lower end of the deflecting plate 12 so as to engage the back surface of the plate while the upper end of the strip 15 is folded back over the upper end of the

110 plate 12 and onto the upper or convex surface. Apertures 16 are provided in the plate 12 near its upper end and another aperture 17 is provided in the rib 13, the

walls of all of these apertures being screw threaded.

A guard plate 18 is adapted to be placed over the deflecting plate 12 and the intermediate portion 5 of the pocket bracket 4, this guard plate having a depending tongue 19 for lapping the outer portion of the pocket bracket. Openings 20 are formed in the guard plate 18 and are adapted to register with the openings 16 and 17.

In applying the attachment to a table having a pocket formed of netting or the like the strip 15 is applied to the deflecting plate 12, slots being preferably cut in the upper end portion of the strip 15 so as to straddle the openings 16 although, if desired, openings may be extended through the strip 15 instead of providing the slots. These slots have been indicated by dotted lines at 21 in Fig. 1. After the parts 12 and 15 have thus been assembled they are inserted into the upper portion of the pocket 11 with the bead 14 extending under the intermediate portion 5 of the bracket 4 and engaging the strip 10 of leather or the like. The rib 13 will thus be positioned within the arc described by the intermediate portion 5 of the bracket. The guard plate 18 is then placed over the intermediate portion 5 of the bracket and over the other portion of the plate 12, this guard plate being dished or concave so that its marginal portion will rest on the strip 10 as shown, particularly in Fig. 3. Screws 22 or other suitable fastening means are then inserted through the openings 20, some of them entering the openings 16 while the other enters the opening 17. By tightening this latter screw the guard plate 18 and the deflecting plate 12 will be drawn toward each other so as to clamp tightly upon the pocket bracket 4 while by tightening the other screws 22 the upper end portion of the strip 15 will be clamped securely between the guard plate 18 and the strip 12.

When the attachment is thus applied it will be obvious that a ball shot through the opening 3 will come against the concave surface of the strip 12 and instead of rebounding back onto the table will be caused to roll downwardly into the pocket.

This attachment can also be used in connection with boots such as are provided in tables of those types utilizing runways leading to a ball box. If preferred, however, a special form of boot can be used, one of these forms being illustrated in Fig. 5. This boot, which can be made of leather or other suitable material and which has been illustrated at 23 can have its upper end extended inwardly toward the table so as to overhang the opening 2, thus to form a curved ball receiving pocket for deflecting balls from the opening 2 to a runway such as shown at 24 and which is located under

the table. The boot can be reinforced by a curved metal tongue 26 arranged along the outer convex surface thereof from the upper to the lower end so as to constitute a stiff backing for the leather whereby the boot will be kept in shape in spite of the continual pounding to which it is subjected by the balls shot into the boot. The lower end of the boot and of the deflecting plate 26 connected thereto can be secured together by rivets 27 or the like while the upper end of the boot is attached by rivets 28 or other suitable fastening devices to a dished guard plate 29. The deflecting plate 26 extends under this guard plate and is fastened thereto by rivets 30 or the like, there being oppositely extending wings or arms 31 integral with the guard plate and which are adapted to be bolted or otherwise fastened to the rail of the table. In this form of device the guard plate 29 and the arms 31 take the place of the guard plates 18 and the pocket bracket 4 hereinbefore described.

It is to be understood that the boot, when engaged by a ball shot through the opening 2 will cause the ball to roll or twirl downwardly as indicated in Fig. 5 so as to pass freely into the runway 24. This boot can be constructed in any way found most desirable in order to give the necessary strength and contour.

It is to be understood that various means other than those described may be employed for deflecting balls into boots already in position in a table or into pockets and runways. The forms shown merely constitute the preferred forms but it is to be understood that in every form used it will be necessary to provide a deflecting plate designed to present an overhanging portion in line with the ball receiving opening so that, as a ball enters said opening, it will be deflected positively in a downward direction and thus prevented from rebounding onto the table.

What is claimed is:

1. The combination with a table having a rail and a ball receiving opening in the rail, of a downwardly and inwardly curved deflecting element extending below the playing surface of the table and having its upper end portion overhanging a portion of the opening and supported in the path of a ball shot into the opening.

2. The combination with a table having a rail and a ball receiving opening in the rail, of a rigid deflecting element in the path of balls directed into the opening and extending below the playing surface of the table, said element having its upper portion curved inwardly to overhang a portion of the opening and to receive a ball thereunder, and a covering material extending from one end to the other of said element for engagement by the ball.

3. The combination with a table having a rail provided with a ball receiving opening, of a guard plate extending over the opening, means for securing the guard plate to the rails, and a curved deflecting element connected to the guard plate and extending below the playing surface of the table, said element having its upper portion overhanging the ball receiving opening.
- 10 4. The combination with a table having a rail provided with a ball receiving opening, of a guard plate bridging the opening, an arcuate deflecting element connected to the guard plate and having its upper end overhanging the path of a ball shot into the opening and its lower end extending below the playing surface of the table and means for securing the guard plate to the rail.
- 15 5. The combination with a table having a rail and a ball receiving opening, of a bracket bridging said opening, a deflecting plate having its upper end overhanging the path of a ball shot into the opening and its lower end extending downwardly below the playing surface of the table, a guard plate, and means for clamping said plate upon the bracket.
- 20 6. The combination with a table having a rail and a ball receiving opening, of a bracket bridging said opening, a deflecting plate having its upper end overhanging the path of a ball shot into the opening and its lower end extending downwardly below the playing surface of the table, a protecting
- 25 covering upon the concave surface of the deflecting plate and straddling the end portions thereof, a guard plate, and means for clamping the plates upon the bracket and upon one end portion of the covering.
- 30 7. The combination with the pocket bracket of a pool table, of a curved deflecting member, a projecting portion thereof for engaging under a portion of the bracket, and a guard plate detachably secured upon the upper portion of the deflecting member and coöperating with the projecting portion to grip the pocket bracket and hold the deflecting member fixed relative to the bracket.
- 35 8. The combination with the pocket bracket of a pool table, of a curved deflecting member, a projecting portion thereon for extending under a portion of the bracket, a protecting strip fitted upon one face of the deflecting member and having one end portion lapping one end of the deflecting member, and a guard plate detachably connected to the deflecting member and coöperating with the projecting portion on said member to clamp a portion of the bracket and hold the deflecting member fixed relative thereto, said guard plate engaging and holding the lapping portion of the protecting strip.
- 40 In testimony that I claim the foregoing as my own, I have hereto affixed my signature in the presence of two witnesses.
